The ornamental design for women's pants, as shown and described.

DESCRIPTION

FIG. 1 is a perspective view of women's pants embodying my new design;

FIG. 2 is a front elevational view thereof;

FIG. 3 is a rear elevational view thereof;

FIG. 4 is a right-side elevational view thereof;

FIG. 5 is left-side elevational view thereof;

FIG. 6 is a top plan view thereof; and,

FIG. 7 is a bottom plan view thereof.

The wavy standard broken lines adjacent to the shaded regions represent a boundary of the claimed design. The rest of the standard broken lines represent portions of the women's pants that form no part of the claimed design. The closely spaced broken lines represent claimed stitching.
